(57) CLAIM

The ornamental design for a mat attachment, as shown and described.

DESCRIPTION

FIG. 1 is a perspective view of a mat attachment;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a top, perspective view of the mat attachment coupled to a mat that is laid flat.

All broken lines of FIGS. 1-7 represent unclaimed features of the article to which the design is applied. The broken line showing of the mat of FIG. 8 is for the purpose of illustrating environmental structure and forms no part of the claimed design.
